COMBINATION METAL AND NONMETAL DRAWER

Earle E. Merrett, Manitowoc, Wis.

Application July 21, 1949, Serial No. 106,000

2 Claims. (Cl. 312—349)

1

The present invention relates to improvements to metal and non-metal constructions, and particularly to metal and non-metal drawer constructions.

One of the primary objects of the present invention is to provide simplified constructions whereby metal and non-metal parts may be readily connected together.

A further object of the present invention is to provide improvements in drawer constructions in which parts of the drawer are constructed of metal and other parts of non-metal material, so that when the drawers are mounted in a cabinet they have the external appearance of wood, and yet the inside has the economy, efficiency, strength and utility of metal.

A further object of the invention is to provide improvements in drawer constructions of the type mentioned in which the tininess present in metal drawer constructions is eliminated and yet the drawer may be smoothly operated in any climate.

A further object of the invention is to provide improvements in drawer constructions in which the drawer is so constructed and mounted in the cabinet that dust or dirt does not drop from one drawer compartment to the next.

Other objects of the invention will become apparent from the following specification, the drawings relating thereto, and from the claims hereinafter set forth.

In the drawings, in which like numerals are used to designate like parts in the several views throughout:

Figure 1 is a perspective view of a combination metal and non-metal drawer construction embodying features of the present invention;

Fig. 2 is a broken, side elevational view of the drawer shown in Fig. 1;

Fig. 3 is a partial, broken, top plan view of the drawer shown in Fig. 1;

Fig. 4 is a broken, cross-sectional view, taken substantially along the line 4—4 of Fig. 3;

Fig. 5 is a perspective view of one of the drawer sides;

Fig. 6 is a partial, broken, vertical cross-sectional view of a cabinet, and showing the manner in which the drawers are mounted therein;

Fig. 7 is a horizontal cross-sectional view, taken through a drawer cabinet, and showing a drawer in place mounted therein;

Fig. 8 is a broken, cross-sectional view, taken substantially along the line 8—8 of Fig. 7;

Fig. 9 is a view similar to Fig. 7, showing another modified form of the present invention;

2

Fig. 10 is a broken cross-sectional view, taken substantially along the line 10—10 of Fig. 9;

Fig. 11 is a top plan view of a boat embodying features of the present invention;

Fig. 12 is a broken cross-sectional view, taken substantially along the line 12—12 of Fig. 11; and

Fig. 13 is a view similar to Fig. 6 illustrating a modified form of the present invention.

In general, it is pointed out that in wooden drawer constructions trouble has been encountered due to the cellular constructions of the wood which absorbs moisture in the summertime so that the drawers stick. Metal drawers have been found to be unsatisfactory because of the tininess inherent in their use, and because of their unorthodox external appearance. The present invention is directed to the utilization of the best features of both wood and metal drawers, and at the same time eliminates the difficulties inherent in them.

Referring to the drawings, and referring particularly to Figs. 1-6, a drawer construction embodying features of the present invention is generally indicated at 1. Such drawer comprises a front 2, sides 3 and 4, a back 5 and a bottom 6. The sides 3 and 4 are constructed of sheet metal, and the front 2, back 5 and bottom 6 are constructed of non-metallic materials, such as solid wood, plywood, or a composition material such as Masonite.

The sides 3 and 4 are of identical construction so that they may be reversed for use on either side. The sides 3 and 4 are each formed of sheet metal having an inwardly directed channel 7 formed along the bottom edge thereof which defines an outwardly directed drawer run 8, which is defined by the top and bottom flanges of the channel 7 and the interconnecting vertical wall thereof. The drawer side 9 extends vertically from the inner edge of the upper channel flange and terminates in an outwardly directed flange 10 and a downwardly directed flange 12. The bottom channel and the upper flanges serve to strengthen and stiffen the drawer sides. Inwardly directed tabs 13 and 14 are punched out of the metal sides 9 adjacent the top thereof and spaced inwardly from the front and rear edges thereof a distance substantially equal to the thickness of the back 5 and that portion of the front 2 which is received between the walls 3 and 4.

The side edges of the non-metal bottom 6 are snugly received within the channel 7 of the sides 3 and 4 so as to mount the bottom to the drawer sides.

The drawer front 2 is formed with an inwardly directed, reduced portion 15 so that the bottom edge rests upon the adjacent forward surface of the bottom 6, and the sides thereof abut against the adjacent vertical surfaces of the sides 3 and 4 at the forward edges thereof. The thickness of the inwardly projecting portion is such that the inner face thereof abuts against the adjacent faces of inwardly struck tabs 13 of the sides 3 and 4. The exposed face of the drawer 2 is such that the bottom edge thereof is flush with the bottom of member 6 and the side edges thereof are flush with the outer surface of channel 7 and the outer surface of flange 12. The bottom 6 is connected to the front 2 by a fastener such as a screw or nail 16. The tabs 13 and 14 are each provided with openings therethrough, and the tab 13 is connected to the inner face of front 2 by a fastener such as a screw or nail 17 at each side thereof. Other fasteners, such as nails, or screws, may be connected to the vertical sides of the inner projecting portion 15 of the front 2 through spaced opening 18 provided in the sides 3 and 4 adjacent the front edges thereof. Similar openings 19 are provided adjacent the rear edges of the sides 3 and 4 for the reception of fasteners to be connected to the rear member 5.

The rear wall 5 rests upon the rear edge of the bottom 6 and is disposed between the sides 3 and 4 against the rear tabs 14. The bottom may be connected to the back by means of fasteners 20, and the back 5 is connected to the tabs 14 at each of the sides by fasteners 21 which pass through openings in the rear tabs 14. The rear wall 5 may be further connected to the sides 3 and 4 by fasteners 22, which pass through the openings 19.

The tabs 13 and 14 serve the important function of preventing the drawer from spreading so that the drawer will not bind in the cabinet.

The front 2 is provided with an upwardly projecting lip 23 along the top edge thereof so that a portion of the lip may be planed off to accommodate the drawers to the climate in which they are used, and thus prevent binding of the drawers at the front.

The flange 10 on drawer sides 3 and 4 is provided with openings 24 therethrough adjacent the front and rear edges thereof, and, depending upon which side of the drawer the side is used on, a rubber grommet 25 is placed in the rear opening 24. This provides a bearing surface against the drawer slide, immediately above, so that a bearing surface will be provided and thus the drawer will not tilt. This acts as a friction stop to keep the drawer from falling out when it is three-quarters pulled.

In Fig. 6, a portion of the vertical side wall of the cabinet is indicated at 26, it being understood that the sides are the same at both sides. Drawer slides 27 are provided for each of the drawers on opposite sides of the cabinet, and at vertically spaced positions thereon. Such slides 27 are metal, channel-shaped members which are fastened to the cabinet walls by means of suitable screw fasteners 28 which are passed through openings therein at spaced points therealong. A rubber bumper may be provided at the back end of the channels which may be bent inwardly to receive the bumper. A fibre member 29, which is complementary in shape to the channel 27, is cemented thereto and slidably receives therein the channel-shaped runs 8 on the

drawer sides so that there is no metal-against-metal contact.

Referring to Figs. 7 and 8, a modified form of the invention is shown in which the sides of the cabinet 26 are illustrated, as well as the rear wall 30. In this modification, the construction is such that the drawer compartments are sealed from each other completely around the sides and back of the drawer when the drawer is in its closed position. This is effected by continuing the channel run 27 around the back as well as the sides, as indicated at 31. The channel 31 is of the same construction as channel 30 and is provided with the fibre liner. The drawer bottom 6 is extended to project beyond the back 5, as indicated at 32. Projecting portion 32 extends completely across the back so that when the drawer is in its closed position the projecting portion is received within the channel formed by member 31 and the liner 29. The sides 3 and 4 have the runs 8 formed along the bottom thereof which are received within the side channels 27 so that one drawer space is sealed from the next drawer space.

In the embodiment shown in Figs. 9 and 10, the same sealing effect as in the embodiments shown in Figs. 7 and 8 is accomplished. However, in this embodiment the back 33 is formed in continuation of the metal sides 3 and 4, and is of the same cross-section, as will be evident by a comparison of Figs. 10 and 4. This is accomplished by notching the corners, as indicated at 34, and bending the metal strip to form the sides 3, the back 33, and the side 4. The bottom 6 is then received within the rear channel 7', which is the same as channel 7 in the embodiment above described. The bottom 6 projects beyond the back 33 and is received within the channel 7' in the same way as the sides and bottom are received within channel 7. The side channels 7 are then received within the channels 27, and the channel 7' is received within the channel 31 along the back. Thus, the drawer compartments are sealed from each other in the same way as the embodiments shown in Figs. 7 and 8.

Referring to Figs. 11 and 12, a structure of the present invention is illustrated as adapted for boat construction. The sides of the boat, as indicated at 4', have the same vertical section as the drawer sides 4. The bottom 6' is shaped to conform to the shape of a boat, with a back 5' mounted thereto and connected to the adjacent ends of the metal sides 4' in the same way that the back 5 is connected to the sides 3 and 4 in the embodiment described above. In other words, the sides 4' are provided with in-struck tabs 14' which are connected to the back 5' in the same manner as tabs 14 to the back 5 in the embodiment above described. The side edges of bottom 6' are received within the channel 7'' in the same way that the sides of bottom 6 are received in channel 7 in the embodiment described above. The vertical juncture line of the sides 4', as indicated at 35, may be brought together and welded. The sides 4'' are metal, and the bottom 6' and back 5' are of non-metal material.

Referring to Fig. 13, a modified form of drawer construction is illustrated. In this construction the drawer is slidably mounted in the drawer slides 27 by means of longitudinally extending channel members 40 which are formed with outwardly disposed flanges 41 and spot welded to the sides 4 midway between the top and bottom edges thereof. There is, of course, a channel member 40 similarly mounted on both sides of the drawer. The channels 27 are then locked in proper spaced

relationship so that the drawers are slidably supported by the mounted channels 40. Such channels extend the full depth of the drawer.

Formal changes may be made in the specific embodiment of the invention described without departing from the spirit of the invention, the scope of which is commensurate with the appended claims.

What is claimed is:

1. A drawer construction comprising non-metallic front, back and bottom members and metallic side members, each of said side members being formed with an outwardly projecting U-shaped flange defining a drawer run and forming an inwardly directed channel along the bottom edge thereof and receiving within said channel the adjacent edge of said non-metallic bottom member, an outwardly and downwardly projecting flange formed on the top edge of each of said side members and having a rubber grommet on the top thereof adjacent the rear thereof inwardly directed tabs formed on said side members adjacent the top thereof and adjacent the inside surfaces of said front and back members in engagement therewith, means connecting said tabs to said front and back members, and means connecting said bottom member to said front and back members.

2. A drawer construction comprising a back

member, non-metallic front and bottom members, and metallic side members, each of said side members being formed with an outwardly projecting U-shaped flange defining a drawer run and forming an inwardly directed channel along the bottom edge thereof and receiving within said channel the adjacent edge of said non-metallic bottom member, an outwardly and downwardly projecting flange formed on the top edge of each of said side members and having a rubber grommet on the top thereof adjacent the rear thereof an inwardly directed tab formed on each of said side members adjacent the top thereof and adjacent the inside surface of said front member, means connecting said tabs to said front member, and means connecting said bottom member to said front and back members.
